Des. 213,164
Patented Jan. 7, 1969

213,164

SODA DRAFT ARM OR SIMILAR ARTICLE

James R. Reichow, Edina, Minn., assignor to The Cornelius Company, Anoka, Minn., a corporation of Minnesota

Filed Jan. 16, 1968, Ser. No. 10,184

Term of patent 14 years

U.S. CL. D94—3
Int. CL. D15—12

FIG. 1 is a side elevational view of a soda draft arm, showing my new design, the opposite side having a reverse appearance.

FIG. 2 is a rear elevational view thereof in reduced scale.

FIG. 3 is a front elevational view thereof.

FIG. 4 is a top plan view thereof.

I claim:

The ornamental design for a soda draft arm or similar article, substantially as shown and described.
